UNITED STATES PATENT OFFICE.

FRANK BOWERS, OF DETROIT, MICHIGAN, ASSIGNOR, BY MESNE ASSIGNMENTS, TO
DIAMOND POWER SPECIALTY CORPORATION, OF DETROIT, MICHIGAN, A CORPORA-
TION OF MICHIGAN.

BOILER-CLEANING DEVICE.

Application filed November 21, 1918, Serial No. 263,476. Renewed September 16, 1925.

This invention relates to boiler cleaners and refers more particularly to boiler cleaners of the type in which steam or other cleaning fluid is discharged against the surfaces 5 to be cleaned by means of a rotatable pipe or blower unit having nozzles or other suitable discharge openings.

Among the objects of the invention are to provide an improved connection between the 10 rotatable blower unit and the source of steam; to provide an improved arrangement of drive mechanism for rotating the unit; to provide a head for the end of the blower unit which can be conveniently manufactured and assembled; and to provide a construction in which both the steam connection and the driving mechanism are completely inclosed within a compact construction.

The invention also resides in the removable 20 cap for the blower unit head and in such further features of construction and arrangements and combinations of parts as will more fully hereinafter appear.

In the drawings:

25 Figure 1 is a view in sectional elevation of a boiler to which the invention is applied; Figure 2 is a fragmentary vertical sectional view showing one arrangement of my invention;

30 Figure 3 is a cross-section on line 3—3 of Figure 2;

Describing in detail the particular construction shown in the drawings, A designates a boiler having a plurality of boiler 35 tubes B, and C designates a blower unit having a plurality of discharge nozzles C' through which steam or other suitable fluid is discharged against the surfaces of the tubes B so as to remove the soot or other 40 accumulations from the boiler tubes.

In boiler cleaners of the type shown it is common to mount the blower unit or pipe C so that it can be rotated through a given arc whereby the steam jets can be discharged 45 against all of the surfaces of the tubes to be cleaned or whatever portion is desired to be cleaned by this unit.

The present invention particularly contemplates an improved means for rotating 50 the pipe C and also an improved connection between the pipe C and the steam conduit D leading from the main steam supply pipe D'. For this purpose I employ a casting or head E which has a cylindrical portion E'

telescopedically engaging an end of the blower 55 pipe C. In order to reduce the friction between the walls of the cylindrical portion E' and the blower unit, the former is cut away at E². The extreme outer end F of the blower unit or pipe C is preferably 60 threaded at F' to receive a worm wheel G which is keyed or otherwise fixed to the pipe to drive the same. The casting E is also provided with a supplemental housing or chamber H in which there is mounted a 65 worm H' meshing with the worm wheel G. The supplemental housing H has suitable bearings I and I' in which the shaft J of the worm H' is mounted, the bearing I' being preferably removable and containing 70 a steam packing I² through which the end of the shaft J extends. For turning the shaft J so as to rotate the worm and worm wheel, whereby the unit C can be operated from a convenient point, the shaft J is provided at its outer end with a chain wheel 75 J' over which there extends a depending chain J².

By employing the removable bushing I' the worm H' can be conveniently inserted 80 and removed from the supplemental housing H, and I provide a similar arrangement for the main part of the housing E whereby the worm wheel G can be conveniently inserted and removed. As shown 85 in Figure 2, the outer end of the housing E has an enlarged threaded opening K into which there is threaded a cap or closure K'. The size of the opening is preferably such as to permit the free insertion of the worm 90 wheel G and after the parts are assembled the cap K' is threaded into the opening K. This cap not only forms a closure for the opening K, but also is provided with a chamber L registering with the open end of the 95 pipe C, and branch passages M leading from the chamber L to the inlet opening M' into which the branch conduit D is threaded. In this manner there is always provided a steam passageway from the branch supply pipe D to the unit C whenever the control valve D² 100 is opened. After opening the valve D², the blower unit or pipe C is rotated by turning the shaft J through the chain J² and wheel J'. This rotary movement of the shaft J is imparted to the blower unit or pipe C by the worm and worm wheel, a slow and steady 105 movement being transmitted to the pipe C

which will prevent its being rotated faster than it will properly clean the surfaces of the tubes B.

To limit the arc through which the unit C can be turned the supplemental housing H is provided with an inwardly extending projection N which forms a stationary stop against which the stops O on the worm wheel G will strike. The stops O are preferably formed as bolts extending through slots Q in the web of said worm wheel and in this manner they can be shifted so as to vary the degree of rotation through which the unit can be turned.

What I claim as my invention is:

1. In a device for cleaning boilers, the combination with a rotatable blower unit and a steam supply pipe, of a fitting establishing a direct connection therebetween comprising a header into which both the steam supply and the blower unit open, said header having a removable cap, and said cap having passageways connecting the blower pipe with the supply pipe.

2. In a device for cleaning boilers, the combination with a rotatable blower unit and a steam supply pipe, of a connection therebetween comprising a header into which both the steam supply and the blower unit open, said header having an opening therein, a cap normally closing said opening, and a gear mounted within said header for rotating said unit; the mounting for said gear

and said opening being so relatively disposed as to permit the gear to be readily inserted into place through said opening in the assembling of the unit, before the cap is applied. 35

3. In a device for cleaning boilers, the combination with a rotatable blower unit 40 and a steam supply pipe, of a connection therebetween comprising a header into which both the steam supply and the blower unit open, said header having an opening therein, a cap normally closing said opening and 45 a worm wheel mounted within said header for turning said blower unit, the mounting for said worm wheel and said opening being so relatively disposed as to permit the worm wheel to be readily inserted into place 50 through said opening in the assembling of the unit, before the cap is applied.

4. In a device for cleaning boilers, the combination with a rotatable blower unit 55 and a steam supply pipe, of a connection therebetween comprising a header into which both the steam supply and the blower unit directly open, said header having a removable cap opposite the blower unit, said unit being extended through the header into 60 proximity to said cap, and the cap being formed with a passageway for delivering steam from the supply pipe to the unit.

In testimony whereof I affix my signature.

FRANK BOWERS.
